UNITED STATES PATENT OFFICE.

JOHN W. NEWMAN, OF RIDGEFIELD PARK, NEW JERSEY.

SEPARATING-TRAP.

1,208,820.

Specification of Letters Patent. Patented Dec. 19, 1916.

Application filed December 28, 1915. Serial No. 69,019.

To all whom it may concern:

Be it known that I, JOHN W. NEWMAN, a citizen of the United States of America, residing at Ridgefield Park, Bergen county, New Jersey, have invented a new and useful Separating-Trap, of which the following is a specification.

My invention relates to devices termed "separating traps" and in the present instance, I have shown and described my invention as applied to steam and water separation.

The object of the invention is to permit condensation to be drawn out of a steam line without allowing the pressure in said steam line to drop.

In the drawings: Figure 1 is a plan view of my invention. Fig. 2 is a side elevation thereof. Fig. 3 is a relatively enlarged 20 sectional view on the line 3—3 of Fig. 1 showing certain parts in elevation. Figs. 4 and 5 are detail views.

1 represents conventionally a steam chamber within which condensation is liable to occur. The problem is to separate, or draw off, the water of condensation without permitting the steam pressure to drop. This I accomplish by the following instrumentality: 2—2 are main supporting blocks upon 25 which is tiltably mounted my improved mechanism which operates after the manner of a walking beam. 3 represents the walking beam proper which is mounted on the supports 2—2 in the manner hereinafter described. 4—5 are tanks suitably mounted on the walking beam 3 at opposite sides of the fulcrum therefor, the fulcrum being so located relatively to the combined weight of the apparatus carried by the walking beam, that the end bearing the tank 4 will normally overbalance the opposite end carrying the tank 5. The walking beam 3 is mounted directly upon a saddle block 6 (Fig. 3) which has at opposite sides tubular 35 extensions 7—8 securely fastened thereto. At the ends of these tubular extensions are packing boxes 9—10, respectively. These tubular extensions have suitably formed bearings which rest upon the supporting blocks 2—2, which latter are formed so as to provide bearing boxes 11—11 which may, if desired, be provided with anti-friction devices to permit the walking beam 3 to oscillate more freely. These tubular extensions 7—8 operate, in effect, as hollow trunnions, and enable me to effect the various 40 water connections with the two tanks respectively without the use of flexible tubing.

I will now describe the piping. A pipe 12 leads down from the chamber to be 60 drained to a back check-valve 13, thence on through pipe 14 through the stuffing box 9, and into the chamber 15 within the trunnion 7. By preference the inner part of this pipe 14 has a bearing shoulder 16 which bears with reasonable snugness against an internal shoulder on the trunnion shown adjacent thereto. 17 is a spring which serves to keep the shoulder 16 in engagement with the internal shoulder on the trunnion. 18 65 is an outlet at the inner end of the pipe 14 which opens into the chamber 15. Proceeding from the trunnion 7 and in communication with the chamber 15 is a pipe 19 which leads into the tank 4 and terminates 70 near the upper part thereof. 20 is an outlet pipe leading from the bottom of the tank 4 across to and into the tank 5 and terminating near the upper part thereof. 21 is a pipe which leads from the bottom 75 of the tank 5 into the trunnion 8 so as to be in communication with the chamber 22 thereon. 23 is a pipe which enters the chamber 22 in the same manner as the pipe 14 enters the chamber 15. This pipe 23 has an 80 opening 24 through which water may flow into the pipe 23. The pipe 23 leads outwardly through the stuffing box 10 and communicates with a discharge pipe 25 in which is located a valve 26 and beyond the valve 90 85 27. The valve 26 is connected in any suitable way as by an arm 28 with part of the tilting mechanism so that when the walking beam stands in the position shown in Fig. 2 the valve 26 will be 95 open, whereas when the walking beam is tilted to the opposite position, the arm 28 will descend and the valve 26 will be shut. Any suitable valve closing means may be provided, as for example, a gravity closer 100 weight 29. 30—30 are vents in the upper parts of the tanks 4—5. 31 is a post which limits the descent of the walking beam 5 at one end while 32 is a post which limits the descent of the walking beam at the other 105 end.

Having now described the various parts of the construction, its operation will be seen to be as follows: I first block up that end of the walking beam supporting the tank 4 so 110 that the opposite end will rest upon the post 32 and the valve 26 will be closed. I then

open the vents in the tanks until the water of condensation will fill both tanks. I then shut the vents and take out the block, after which the trap will work automatically as follows: Upon the taking out of the block the tank 4 will descend, by reason of the fact that it will then overbalance the opposite end of the tilting mechanism. This movement will open the valve 26 whereupon the water in tank 5 will commence to flow out. It is preferable that the capacity of the pipe 25 should be such that the water will not flow out at a more rapid rate than it can flow into the tank 5 from the tank 4. Now, as the water flows out of tank 5, it will tend to create a partial vacuum which tends to draw the water from the bottom of tank 4. So far as there is any pressure in tank 4, this pressure will also tend to assist in the flow of the water from the tank 4 into the tank 5 through pipe 20, so as to supply the tank 5 with water as rapidly as water is being drained from the latter, whereby the tank 5 will remain full or substantially full, the level being lowered in tank 4 during the discharge period. When finally sufficient water has been drawn from tank 4 to make that end of the tilting mechanism lighter than the opposite end, the latter end will drop and the walking beam 3 will elevate the tank 4 and close the valve 26. When the level of water in tank 4 is again raised to a point where it overbalances in weight, the opposite end of the tilting mechanism, the beam 5 will tilt back to the position indicated in Fig. 2 and the emptying process will again take place. By this means, after the trap is once started, it will automatically tilt to and fro so as to periodically discharge the water of condensation without allowing the steam pressure to lower. Obviously the check valves 13—27 may not be employed in all cases, for example, where there is no tendency to back pressure, but when there is a tendency to back pressure such check valves are desirable. In some cases it may be necessary to use high pressure steam for forcing the discharge from the trap to a boiler or to an elevated tank which will be understood by those familiar with this art. In such case, the high pressure steam will be admitted at the same time that the outlet valve is opened and closed when the outlet valve is closed.

In the preferred construction, such as I have employed with marked success, I have observed the following proportions in the use of tanks with approximately fifteen and a quarter gallons capacity each. The introductory pipe 14 is one inch in diameter, the connecting pipe 20 an inch and a half in diameter, and the discharge pipe 25 a half an inch in diameter. It is also desirable to have the bearing shoulder 16 and its co-⁶⁵ operating shoulder, as provided on each of

the pipes 14 and 23, ground or otherwise fitted so as to make a practically water tight joint thus relieving the work of the stuffing boxes 9—10, and in some instances making the stuffing boxes unnecessary. The oscillatory movement being very slight, the wear on the various connections is correspondingly slight. In some instances it may also be desirable to hold the pipes 14 and 23 close to the trunnions 7—8 to prevent said pipes from turning, in which event, I provide the holding pedestals 33—33.

What I claim is:

1. A separating trap comprising two tanks of the same capacity, a walking beam supporting said tanks and having hollow trunnions, one of said tanks being mounted at a materially greater distance than the other from the trunnions, a support for said tanks and walking beam through the medium of said trunnions, a pipe leading into one of said tanks through one of said trunnions, another pipe leading from the last mentioned tank to the other tank, and another pipe leading from the last mentioned tank to the other trunnion, and another pipe leading from the last mentioned tank to the other trunnion, a valve in said last mentioned pipe, with means for controlling said valve by the relative position of said walking beam.

2. In a separating trap, a main support, tiltable mechanism mounted thereon including a walking beam having hollow trunnions mounted in said support, two separate tanks of the same capacity mounted on opposite ends of said walking beam, one end of said tiltable member being heavier than the other, a pipe system leading through one of said trunnions and into the tank on the heavier side of the trunnion, another pipe leading from the last mentioned tank to the tank on the lighter side of said tilting mechanism, another pipe leading through the other trunnion to an outlet, a valve in said outlet, and means of connection between said tiltable mechanism and said valve for opening the same when said tiltable mechanism stands in one position.

3. In a separating trap, a main support, tiltable mechanism mounted thereon including a walking beam having hollow trunnions mounted in said support, two separate tanks mounted on opposite ends of said walking beam, one end of said tiltable member being heavier than the other, a pipe system leading through one of said trunnions and into the tank on the heavier side of the trunnion, another pipe leading from the last mentioned tank to the tank on the lighter side of said tilting mechanism, another pipe leading through the other trunnion to an outlet, a valve in said outlet, means of connection between said tiltable mechanism and said valve for opening the same when said tiltable mechanism stands in one position, the outlet

being of smaller capacity than the inlet and the passage connecting the separate tanks being larger than the outlet.

4. In a separating trap, a tiltable walking beam having trunnions, a mounting therefor, two tanks carried one at each end of said walking beam, said trunnions being located nearer to one end than to the other, an introductory pipe leading through one trunnion into the upper part of the tank on the longer end of the walking beam, another pipe leading from the lower part of said tank into the upper part of the other tank, another pipe leading from the lower part of the last mentioned tank through the other trunnion and a discharge pipe leading from the last mentioned trunnion, a valve in said pipe with means of connection between said valve and walking beam whereby when the longer end of said walking beam is down, said valve will be open and vice versa.

5. In a separating trap, a walking beam having hollow trunnions at opposite sides thereof, bearing supports for said trunnions, two tanks carried by said walking beam at opposite sides of said trunnions all constituting a tiltable mechanism, one end of which normally overbalances the other, each of said trunnions having a hollow chamber, a pipe entering one trunnion from one end with means for forming a substantially water-tight joint between said pipe and trunnion, said pipe opening into the chamber of said trunnion, another pipe leading from the lower part of the last mentioned tank into the upper part of the other tank, another pipe leading from the lower part of the last mentioned tank to the other trunnion and opening into the chamber thereof, another pipe leading longitudinally through the last mentioned trunnion and having an opening into said chamber with a valve in the outer part of the last mentioned pipe, and means of connection between said tiltable mechanism and said valve for controlling said valve by the position of said member, with a check valve in the first mentioned pipe and with another check valve in the last mentioned pipe beyond the valve therein.

ling said valve by the position of said member. 50

6. In a separating trap, a walking beam having hollow trunnions at opposite sides thereof, bearing supports for said trunnions, two tanks carried by said walking beam at opposite sides of said trunnions all constituting a tiltable mechanism, one end of which normally overbalances the other, each of said trunnions having a hollow chamber, a pipe entering one trunnion from one end with means for forming a substantially water-tight joint between said pipe and trunnion, said pipe opening into the chamber of said trunnion, another pipe leading from the lower part of the last mentioned tank into the upper part of the other tank at the heavier end of said tiltable mechanism, another pipe leading from the lower part of the last mentioned tank into the upper part of the other tank, another pipe leading from the lower part of the last mentioned tank to the other trunnion and opening into the chamber thereof, another pipe leading longitudinally through the last mentioned trunnion and having an opening into said chamber with a valve in the outer part of the last mentioned pipe, and means of connection between said tiltable mechanism and said valve for controlling said valve by the position of said member, with a check valve in the first mentioned pipe and with another check valve in the last mentioned pipe beyond the valve therein. 70

7. In a separating trap, the combination of a beam, a tank mounted on each end of said beam, each of said tanks being cylindrical in form and mounted with their axes transverse to the length of said beam, a pivotal support for said beam located nearer one of said tanks than the other, an inlet pipe leading into the upper part of the tank on the longer arm of said beam, a connecting pipe 85 leading from the bottom of said tank to the upper part of the other tank, an outlet pipe leading from the lower part of said second tank and means for controlling the flow of liquid from said second tank.
